(57) **CLAIM**

The ornamental design for a measuring roller device, as shown and described.

DESCRIPTION

FIG. 1 is an isometric side view of the measuring roller device of our new design;

FIG. 2 is a transparent isometric side view of a lower portion of the device of FIG. 1 for illustrative purposes only;

FIG. 3 is a bottom or underplan view of our design;

FIG. 4 is a top or plan view of our design;

FIG. 5 is a right side view of our design;

FIG. 6 is a left side view of our design;

FIG. 7 is a front view of our design; and,

FIG. 8 is a rear (user side) view of our design.
